UNITED STATES PATENT OFFICE.

EDWIN B. RAYNER, OF PIQUA, OHIO, ASSIGNOR TO AUGUSTUS G. KERNS,
OF SAME PLACE.

STEAM VACUUM-PUMP.

SPECIFICATION forming part of Letters Patent No. 663,041, dated December 4, 1900.

Application filed January 29, 1900. Serial No. 3,246. (No model.)

To all whom it may concern:

Be it known that I, EDWIN B. RAYNER, a citizen of the United States, residing at Piqua, in the county of Miami and State of Ohio, 5 have invented certain new and useful Improvements in Steam Vacuum-Pumps; and I do hereby declare the following to be a full, clear, and exact description of the invention, such as will enable others skilled in the art to 10 which it appertains to make and use the same.

This invention relates to apparatus for raising water or other liquids where it is desirable and most profitable to take advantage of high and low pressures of steam in 15 the same machine.

An essential feature of the invention is the provision of a steam vacuum-pump that will operate successfully with steam at a comparatively low pressure, utilize the motive agent 20 to the best possible advantage, and be entirely automatic, positive, and certain in action.

With these and such other ends in view as appertain to the nature of the invention and 25 for a full disclosure thereof and also to acquire a knowledge of the details of construction of the means for effecting the result reference is to be had to the following description and the drawing hereto attached.

30 While the essential and characteristic features of the invention are necessarily susceptible of modification, still the preferred embodiment of the invention is illustrated in the accompanying drawing, which is a vertical central section of a pump of the character aforesaid for attaining the objects of the invention.

The drum or casing 1 is preferably of circular outline in transverse section, and may 40 be of any length and diameter, and is provided at its upper end with a head 2 and at its lower end with a head 3, to which is attached a bowl 4 or like device, by means of which the pump is adapted to be connected 45 to the suction-pipe dipping into the water or liquid to be elevated. The lower head 3 is provided at a central point with a tubular guide 5 and with a series of openings 6, controlled by means of upwardly-opening valves 50 7. An annular wall 8 is attached at its lower end to the head 3, and is spaced from the drum or casing 1, and terminates at its up-

per end about midway of the distance between the heads 2 and 3, the upper end portion being inwardly deflected, so as not to be 55 engaged by the lower end of the wall 9, pendant from the piston 10, located in the casing and adapted to reciprocate vertically therein. An annular flange 11 is provided on the top side of the head 3, and the lower ends of the 60 walls 1 and 8 are attached to opposite sides thereof.

A relief-valve 12 is applied to the head 2 and affords an escape for the air contained in the casing when starting or priming the 65 pump. A valve-casing 13 is located centrally of the head 2, and is in communication with the casing, and is provided with a lateral extension 14, to which the steam-generator or other source of supply of motive agent 70 is connected, and this casing is formed with a valve-seat 15 and a cylinder extension 16 in line therewith. The operating-rod 17 is located centrally of the casing and passes axially through the valve-casing 13 and is provided at its upper end with a piston 18 to operate in the cylinder 16 and with a valve 19 to perch upon the seat 15. The piston 18 and valve 19 are spaced apart, and the latter is of greater superficial area than the former, 80 so as to be held seated by the direct pressure of the steam thereon when closed. A lever 20 is fulcrumed to the upper end of an arm 21, pivotally connected at its lower end to the valve-casing 13 and has its inner end 85 attached to the upper end of the rod 17 and its outer end provided with a weight 22, the latter serving as a counterbalance for the rod 17 and the parts attached thereto.

A stop 23 is secured to the upper portion 90 of the rod 17, and a corresponding stop 24 is attached to the lower end portion thereof. The piston 10 is arranged for operation between the stops 23 and 24 and moves the rod 17 upward upon its ascent, so as to unseat 95 the valve 19, and is adapted to effect a downward movement of said rod upon descending to cause the valve 19 to become seated and shut off the supply of steam. This piston 10 is of annular formation and is of a diameter 100 to move freely in the casing, the upper end of the wall 9 being attached thereto and said wall extending into the annular space formed between the walls 1 and 8. This annular

space 25 is adapted to be filled with a suitable liquid, as oil, to provide a liquid seal for the lower end of the space or chamber inclosed by the wall 9, so as to prevent contact of the steam with the water in the lower portion of the casing when the steam is exerting a positive pressure upon the upper surface of the piston. The central opening 26 of the piston flares at its lower end and is closed at its upper end by means of a puppet-valve 27, whose stem 28 is provided with a stop 29, which limits the vertical movement of the valve when unseated.

The outlet 30 for the water or other liquid is provided at the lower end of the casing and is in communication with a box or analogous device 31, attached to the side of the casing and closed by means of an upwardly or outwardly opening valve 32. In this connection it is to be understood that the discharge-pipe is to be connected with the part 31 and is adapted to convey the water to the surface or other convenient point of discharge.

When in position the pump will have its lower end attached to the suction-pipe and the part 31 to the discharge-pipe. Upon pressing downward upon the outer end of the lever 20 the valve 19 will be unseated, and the steam from the source of supply will rush into the upper portion of the casing through the opening in the lower part of the valve-casing 13, and the steam exerting a downward pressure upon the piston 10 will cause it to descend, and at a predetermined point in its downward travel the stem 28 will engage with the stop 24 and move the rod 17 downward, seat the valve 19, and cut off the supply of steam. At or about the instant the supply of steam is cut off the valve 27 is unseated and the steam above the piston 10 will pass through the opening 26 and into the lower portion of the casing, when condensation will take place and produce a vacuum within the cylinder which will cause the valve 7 to open upwardly and the water or liquid to enter the casing, and this water coming in contact with the steam will effect a condensation of every particle and, rising in the casing, will cause the piston 10 to move upward until brought into contact with the stop 23, when the valve 19 will be automatically unseated and the steam again enter the upper portion of the casing and effect a repetition of the operation just described. In the second and subsequent descending movements of the piston 10 the water contained in the casing will be forcibly expelled through the outlet 30 and by the valve 32, the latter closing the instant the descent of the piston is checked. The valve 12 is opened when starting the pump in order to relieve the casing of the air contained therein, and when the pump is primed or started the said valve 12 is closed and remains shut. After being started the operation of the pump is entirely automatic, the direct pressure of the steam causing the piston to descend and the

vacuum produced by the condensation of the steam causing the water to flow through the valve-controlled openings 6 into the casing and buoying the piston upward as it rises. When the valve 19 is unseated, it is held open by the pressure of the steam until closed by the contact of the stem 28 with the stop 24 and remains closed during the filling of the casing and the ascent of the piston.

To prevent the escape of steam from the upper portion of the casing above the piston to the lower portion of the casing below the piston through the valve-stem 28, the lower end of said stem is preferably partitioned to form the wall of a stuffing-box 28^a, in which are inserted packing 28^b and a gland or hollow nut 28^c, coöperating in the usual manner to form a steam-tight joint between the tube 85 and rod 17. Any other suitable seal or fitting of this character may, however, be employed.

Having thus described the invention, what is claimed as new is—

1. In a steam vacuum-pump, and in combination, with the casing, provided with the valve-controlled inlet and outlet openings, and a piston mounted for reciprocation within the said casing, a valve-casing having a steam-inlet and a valve-seat and cylinder upon opposite sides of the said steam-inlet, a rod provided with stops to be alternately engaged by means of the piston, a valve and a piston secured to the said rod and adapted to coöperate with the seat and cylinder of the aforesaid valve-casing, said valve being of greater superficial area than the piston connected therewith, substantially as and for the purpose specified.

2. In a steam vacuum-pump, a casing provided at its lower end with valve-controlled inlet and outlet openings, and having a guide applied to its lower head, a valve-casing applied to the upper head and formed with a steam-inlet, a valve-seat and a cylinder, a rod passing through the casing and having its lower end coöperating with the guide applied to the lower head thereof, a valve and a piston secured to the upper end of said rod and coöperating with, respectively, the valve-seat and cylinder of the aforesaid valve-casing, upper and lower stops secured to said rod, a piston mounted for reciprocation within the casing and having a centrally-disposed opening, and a puppet-valve for controlling the opening in the piston and having its stem provided with a stop, the supply of the steam being automatically admitted and shut off by the action of the piston, substantially in the manner specified.

3. In a steam vacuum-pump, a casing provided with valve-controlled inlet and outlet openings, and having a valve-controlled steam-inlet, a piston mounted for reciprocation within the casing and having a pendent wall to enter an annular space provided at the lower end of the casing and containing a sealing liquid, said piston controlling the ad-

mission of the steam and provided with a valve-controlled opening, substantially as set forth.

4. In a steam vacuum-pump, a casing provided at its lower end with valve-controlled inlet and outlet openings for the water to be elevated, and provided at its upper end with a valve-controlled inlet-opening for the motive agent, an inner wall secured to the lower portion of the casing and spaced therefrom; said space being adapted to receive a sealing liquid, an annular piston mounted for reciprocation within the casing and having a pendent wall extending into the space formed between the inner and outer walls of the casing, said piston being adapted to alternately open and close the valve regulating the admission of the steam, and a valve applied to the piston for controlling the opening thereof, substantially as set forth.

5. The herein-described steam vacuum-pump, comprising a casing, having an annu-

lar space at its lower end and provided with valve-controlled inlet and outlet openings, a valve-casing applied to the upper head of the 25 casing, and formed with an inlet-opening, a valve-seat and a cylinder, a counterbalanced rod passing through the casing and coöperating with a lower guide thereof, and having upper and lower stops, a piston and a valve 30 secured to the upper portion of said rod and coöperating with the valve-seat and cylinder of the said valve-casing, an annular piston mounted for reciprocation within the casing, and having a pendent wall extending into 35 the aforesaid annular space of the casing, and a puppet-valve applied to said piston, substantially as set forth.

In testimony whereof I affix my signature in presence of two witnesses.
